UNITED STATES PATENT OFFICE

NICKOLAS J. DZIEDZIC, OF CHICAGO, ILLINOIS, ASSIGNOR TO SWIFT AND COMPANY, OF CHICAGO, ILLINOIS, A CORPORATION OF ILLINOIS

FOOD PRESS

Application filed September 28, 1931. Serial No. 565,496.

This invention appertains to compress apparatus and specifically to a press designed for shaping meat.

The invention relates to the type of press including a compression box, a plunger and an ejector.

In accordance with the invention, trip means are provided to automatically and positively position the lifter to engage the stem of the ejector for removal of the compressed product from the compression box on the up stroke of the plunger.

An embodiment of the invention is illustrated in the accompanying drawings in connection with a press comprising a compression box, a plunger, an ejector and connecting means between the plunger and ejector.

The invention consists of the novel features set forth more fully hereinafter in the specification and illustrated in the drawings hereto attached and outlined in the appended claims.

Referring to the drawings:

Figure 1 is a perspective view of a press illustrative of an embodiment of the invention.

Fig. 2 is a side view.

Fig. 3 is a front view.

Fig. 4 is a horizontal section on the line 4-4 of Fig. 2.

Fig. 5 is a top plan view.

Fig. 6 is a detail perspective view of the ratchet wheel and cooperating pawl.

Fig. 7 is a side view of the parts illustrated in Fig. 6.

Corresponding and like parts are referred to in the following description and indicated in the several views of the drawings by like reference characters.

The framework of the press comprises a base 1, an upright 2 having an overhanging portion 3, and a compression box 4 removably fitted upon the base 1. A stem 5 is mounted in the overhanging portion 3 of the upright 45 and is provided along a side with teeth which are in mesh with a gear wheel 6 secured to a power shaft 7 which is mounted in the overhanging portion 3.

A plunger 8 is provided at the lower end 50 of the stem 5 and is adapted to obtain a snug

fit in the compression box 4. An ejector 9 normally rests upon the bottom of the compression box 4 and a stem 10 coacts therewith to effect a lifting thereof for removal of the product from the box 4 after being compressed. The stem 10 is mounted in the base 1 and operates through the bottom of the box 4 to effect vertical movement of the ejector 9 when the stem 10 is moved upwardly.

Connecting means transmit movement from the plunger stem 5 to the stem 10 of the ejector and comprise a rod 11 which is mounted in the base 1 to slide and turn therein. An arm 12 rigidly connected at one end with the stem 5 loosely engages the upper end of the rod 11 whereby to admit of said rod having a rotary movement. Stop collars 13 and 14 are secured to the upper end of the rod 11 and receive the outer end of the arm 12 therebetween. An arm 15 is fast 60 to the rod 11 and projects laterally therefrom and constitutes a handle and an element of a trip mechanism whereby the rod 11 is automatically turned to position the lifter for effecting an upward movement of 65 the ejector when the plunger is approaching the limit of its downward movement. The lifter 16 consists of an arm which is fast to the lower end of the rod 11. An angle plate 17 is secured to the lower portion of the upright 2 and the upper portion of the outwardly disposed flange is cut away to provide a cam 18 which engages the arm 15 and effects a turning of the rod 11 to bring the outer end of the arm or lifter 16 in the path 70 of the stem 10 so that when the plunger moves upwardly the lifter comes in contact with the stem 10 and elevates the ejector to remove the compressed product from the box 4.

A ratchet wheel 19 is secured to the shaft 7 and a pawl 20 cooperates therewith to hold the plunger in an adjusted position. The pawl 20 is provided with a tail piece 21 which constitutes a finger piece to be pressed upon 90 by a digit of the hand when it is required to disengage the pawl 20 from the ratchet wheel 19 so that the shaft 7 may be reversely rotated to lower the plunger 8. A projection 22 overhangs the tail piece 21 and is 100

attached to a laterally projecting portion of the part 3. The pawl 20 has a weighted extension 23 which assures positive engagement of the pawl with the teeth of the ratchet wheel 19.

The cut of meat or other article to be compressed is placed within the box 4 after which pawl 20 is disengaged from ratchet wheel 19 and the shaft 7 is operated by hand or other 10 determinate way to effect a lowering of the plunger. As the plunger 8 reaches the limit of its downward movement the arm 15 makes contact with and rides upon the cam 18 with the result that the rod 11 is partially rotated 15 to bring the lifter 16 in the path of the stem 10. Stop means limit the turning of the rod 11 and consist of a pin 24 projecting from the collar 14 and a pin 25 depending from the arm 12. After the meat or other article 20 has been subjected to the predetermined pressure the pawl 20 is permitted to engage ratchet wheel 19 and the plunger is elevated by a reverse rotation of the shaft 7, being held clear of box 4 by the engagement of 25 pawl 20 with ratchet wheel 19 while box 4 is being reloaded with product.

As the plunger reaches the limit of its upward movement the lifter 16 comes in contact with the stem 10 and a continued upward movement of the plunger effects a corresponding lifting of the stem 10 and ejector 9 with the result that the compressed product is displaced and brought to a convenient position for ready removal from the press.

What is claimed is:

1. In a press including a compression box, a plunger, an ejector and lifter, a rod having the lifter connected thereto and having a swivel connection with the plunger to move therewith and turn independently thereof, and trip means for automatically turning the rod to position the lifter in the path of the ejector, said trip means including an arm rigidly connected to the said rod, and a cam mounted upon the supporting frame.

2. A press comprising a compression box, a plunger, an ejector and lifter, a rod mounted to both slide and turn, an arm rigidly connected with the stem of the plunger and having a swivel connection with the said rod, the lifter being rigidly connected to said rod to move and turn therewith, and trip means for automatically turning said rod, the same comprising a cam mounted upon the framework, and an arm projecting from the said rod.

3. A press comprising a compression box, a plunger, an ejector, a rod mounted to both slide and turn, a lifter rigidly connected with said rod, an arm fast to the stem of the plunger and having swivel connection with the said rod, stop means for limiting the turning of the rod to insure proper positioning of the lifter, an arm projecting from the rod, and a cam adapted to engage said arm to effect

automatic turning of the rod to position the lifter for actuating the ejector.

Signed at Chicago, in the county of Cook and State of Illinois, this 25th day of September, 1931.

NICKOLAS J. DZIEDZIC.
